United States Patent Office.

JAMES W. CHENEY AND BROWN INGALLS, OF SHELBYVILLE,
ILLINOIS.

Letters Patent No. 91,715, dated June 22, 1869.

IMPROVEMENT IN CHURN-DASHERS.

The Schedule referred to in these Letters Patent and making part of the same.

To all whom it may concern:

Be it known that we, JAMES W. CHENEY and BROWN INGALLS, of Shelbyville, in the county of Shelby, and in the State of Illinois, have invented certain new and useful Improvements in Churn-Dashers; and do hereby declare that the following is a full, clear, and exact description thereof, reference being had to the accompanying drawings, and to the letters of reference marked thereon, making a part of this specification.

The nature of our invention consists in the construction and general arrangement of a "churn-dasher," as will be hereinafter fully set forth.

In order to enable others skilled in the art to which our invention appertains, to make and use the same, we will now proceed to describe its construction and operation, referring to the annexed drawings, in which—

Figure 1 is a plan view;

Figure 2, a side elevation; and

Figure 3, a vertical section.

A represents a vertical shaft, to the lower end of which are secured three circular perforated plates, B B', placed a suitable distance apart.

The holes or perforations in these plates are situated diagonally over each other, which arrangement tends to completely separate the cream and form butter.

Each circular plate, toward the top, is smaller in diameter than the one immediately below, thereby allowing an easy return of the cream to the bottom of the

churn on raising the dasher, and, at the same time, churning very effectively both in lowering and raising the dash.

Between the circular plates B and B', and between B' and B", are placed two movable perpendicular perforated dashers C C, which move in and out, to and from the centre, in grooves on the circular plates.

The object of these perpendicular dashers is to gather the butter together after it has formed, by turning the dash to the right or left.

They also add strength to the whole dasher, and can be moved out from the centre, so as to make the dash fit a jar or churn.

We do not confine ourselves to any certain number of circular plates on the central shaft A, as any number desired may, of course, be placed on the shaft.

Having thus fully described our invention,

What we claim as new, and desire to secure by Letters Patent, is—

The combination of the vertical shaft A, circular perforated plates B B' B", and movable perpendicular dashers C C, all constructed and arranged substantially as and for the purposes herein set forth.

In testimony that we claim the foregoing, we have hereunto set our hands, this 14th day of April, 1869.

JAMES W. CHENEY.

BROWN INGALLS.
